ELECTRIC SADIRON

Edward D. Perry, Waterbury, Conn., assignor to
The Beardsey & Wolcott Manufacturing Company, Waterbury, Conn., a corporation of Connecticut

Application August 3, 1931, Serial No. 554,640

8 Claims. (Cl. 219—25)

This invention relates to electric flat-irons or sad-irons, and more particularly to a device of this nature having a thin sole plate which may be readily stamped from sheet metal, and which will permit a rapid and even distribution of heat to the article being ironed.

A further object is to provide a device of the above nature which will be relatively simple in construction, inexpensive to manufacture, easy to assemble and manipulate, compact, ornamental in appearance, and very efficient and durable in use.

With these and other objects in view there have been illustrated on the accompanying drawing two forms in which the invention may be conveniently embodied in practice.

In the drawing:

Fig. 1 represents a longitudinal fragmentary sectional view of a flat-iron embodying the invention.

Fig. 2 is a longitudinal sectional view of the sole plate, as it appears before assembly to the filler block of the flat-iron.

Fig. 3 is a similar longitudinal sectional view of the sole plate illustrating a modified form of attachment to the filler block.

Referring now to the drawing in which like reference numerals denote corresponding parts throughout the several views, the numeral 10 indicates a sole plate employed in the first form of the invention, said sole plate being relatively thin and adapted to be manufactured from sheet metal by stamping in a press. The sole plate 10 is provided in its upper surface, near its ends, with a pair of circular recesses 11 and 12, which are preferably machined out to about one-half the thickness of said sole plate leaving a pair of upstanding annular ribs 13 and 14 which are initially formed vertical, as shown in Fig. 2.

The sole plate 10 is adapted to be connected to a weighted filler block 15 by spinning or staking over the ribs 13 and 14 inwardly upon the beveled annular surfaces of the flat-bottomed heads 16 and 17 of a pair of vertical screws 18 and 19, said screws being securely held in the locked position shown in Fig. 1 by means of a pair of nuts 20 and 21 screwed upon the upper ends thereof. The filler block 15 is provided with a central vertical aperture 22 opening into a longitudinal bottom chamber 23, within which is located a thermostatic control unit 24 having a pair of exterior wires 25 and 26 depending from a pair of binding posts 27 and 27a. The wires 25 and 26 are connected at their lower ends to an electrical heating unit 27b provided with upper and lower

insulating sheets 28 and 29, preferably of mica, and said unit is adapted to be held tightly between the filler block 15 and the sole plate 10 by the screws 18 and 19, mentioned above.

Heating current is adapted to be supplied to said heating unit in any suitable manner, as by a pair of conductor wires 30 and 31 connected by binding posts 32 to a pair of inclined terminal pins 33 adapted to receive an electric socket plug not shown. The terminal pins are adapted to be supported in position by a Z-shaped bracket member 34 having an apertured base 35 surrounding the screw 19 and held tightly in a recess 35a in the filler block 15 by the nut 21.

The thermostatic unit 24 is adapted to be manually controlled by means of a rotatable lever 36 carried on a vertical adjusting shaft 36a. The lever 36 has a raised handle 37 at one end and a pointer 38 at its other end, said pointer being adapted to pass over a dial plate mounted on top of a hollow cover plate 40. The base of the cover plate 40 is adapted to be held tightly against the sole plate 10 by means of a pair of vertical screws 41 and 42 passing through apertures in an upstanding handle bracket 43 and adapted to screw into a pair of tapped sockets 44 and 45 formed in said filler block 15, as clearly shown in Fig. 1.

The modified form of the invention shown in Fig. 3 is similar in all respects to the first form shown in Figs. 1 and 2 with the exception that provision is made of a pair of tapped bushings 46 and 47 having lower flanges 48 and 49 which are located within the central recesses of a sole plate 50, said flanges 48 and 49 being secured to said sole plate 50 by spinning or staking the annular ribs 13 and 14 inwardly, as before. The tapped bushings 46 and 47 are adapted to receive a pair of screws 51 and 52 having slotted upper heads 53 and 54 located in recesses formed in the upper surface of the filler block 15.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a sad-iron, a filler block, a thin sheet

- metal sole plate having a pair of upstanding annular ribs, said ribs being surrounded by an annular recess and being flush with the surface of said sole plate, and a pair of screw bolts having 5 their heads seated within said ribs, nuts for fastening said bolts to said filler block, said annular ribs being bent inwardly upon the heads of said bolts to lock said sole plate upon said sad-iron.
- 10 2. In a sad-iron having a filler block, a thin stamped metal sole plate having an upstanding annular rib, said rib being surrounded by an annular recess and being flush with the surface of said sole plate, a screw bolt having its head seated 15 in said rib and located within said filler block, a nut for fastening said screw bolt to said filler block, said annular rib being bent over on the head of said screw bolt to lock said filler block and sole plate together.
- 20 3. In a sad-iron having a filler block, a thin stamped metal sole plate provided with a recess in its upper surface an upstanding annular rib located in said recess and being initially flush with the surface of said sole plate, a screw bolt 25 having a beveled head with a flat base seated in said rib and connected to said filler block, a nut for fastening said screw bolt to said filler block, said annular rib being bent over on the head of said screw bolt to lock said filler block and sole 30 plate together.
4. In a sad-iron, a filler block, a thin metal sole plate having a recessed section, means connected to said filler block and having a head seated in said recess, and means integral with said sole 35 plate in said recess spaced from the edge thereof initially flush with the surface of said sole plate and bent down over said head for connecting said filler block to said sole plate.
5. In a sad-iron, a filler block, a thin metal sole plate having a recessed section extending about one-half way through the thickness thereof, means connected to said filler block and having a head seated in said recess, and means integral with said sole plate in said recess spaced from the edge thereof initially flush with the surface of said sole plate and bent down over said head for connecting said filler block to said sole plate. 5
6. In a sad-iron, a filler block, a thin metal sole 10 plate having a recessed section, means connected to said filler block and having a head seated in said recess, and an annular rib in said recess initially flush with the surface of said sole plate and bent down over said head for connecting said 15 filler block to said sole plate, said rib being spaced from the edge of said recess to permit the insertion of a bending tool.
7. In a sad-iron having a filler block, a thin metal 20 sole plate having a recessed section, means connected to said filler block and having a beveled head seated in said recess, and means integral with said sole plate in said recess spaced from the edge thereof initially flush with the 25 surface of said sole plate and bent down over said head for connecting said filler block to said sole plate.
8. In a sad-iron, a filler block, a thin metal sole plate having a recessed section for receiving 30 the head of a member for attaching said filler block to said sole plate, and an annular rib initially flush with the surface of said sole plate and integral therewith, and bent down over said head to lock it upon said sole plate. 35

EDWARD D. PERRY.
